(57) **CLAIM**

The ornamental design for a portion of a vehicle rear light assembly, as shown and described.

DESCRIPTION

FIG. 1 is a perspective view of a portion of a vehicle rear light assembly showing our new design;

FIG. 2 is a side elevational view thereof;

FIG. 3 is a rear elevational view thereof;

FIG. 4 is a perspective view of an alternative and substantial mirror image embodiment to the portion of a vehicle rear light assembly as shown in FIGS. 1-3;

FIG. 5 is a side elevational view of the portion of a vehicle rear light assembly as shown in FIG. 4; and,

FIG. 6 is a rear elevational view of the portion of a vehicle rear light assembly as shown in FIG. 4.

The broken line showing of the surrounding portions of the vehicle is for illustrative purposes only and forms no part of the claimed design.
